ELLIS PLUMLEY INVENTOR
BY Victor J. Evans ATTORNEY

UNITED STATES PATENT OFFICE.

ELLIS PLUMLEY, OF CEREDO, WEST VIRGINIA, ASSIGNOR OF ONE-HALF TO MALTA PLUMLEY, OF RUSSELL, KENTUCKY.

MINING MACHINE.

Application filed March 14, 1924. Serial No. 699,290.

To all whom it may concern:

Be it known that I, ELLIS PLUMLEY, a citizen of the United States, residing at Ceredo, in the county of Wayne and State 5 of West Virginia, have invented new and useful Improvements in Mining Machines, of which the following is a specification.

This invention relates to mining machines, and more particularly to a hand 10 operated machine.

One of the main objects of the invention is to provide a machine of simple construction and operation which may be quickly and easily adjusted for adjusting the boring tool or bit for boring a hole at the desired angle. A further object is to provide simple and efficient means for mounting the feed shaft and associated parts in such manner as to facilitate turning thereof for suitably positioning the boring tool. Another 15 object is to provide simple and efficient means for securing the feed shaft and associated parts in adjustment. Further objects will appear from the detail description. 20

In the drawings:

Fig. 1 is a front view of the machine as used;

Fig. 2 is a fragmentary rear view of the machine on an enlarged scale;

Fig. 3 is a section taken substantially on line 3—3 of Fig. 1;

Fig. 4 is a section taken substantially on line 4—4 of Fig. 1;

Fig. 5 is a detail of the feed nut and associated parts;

Fig. 6 is a section taken substantially on line 6—6 of Fig. 5.

The machine includes a supporting frame 40 1 of substantially elongated U-shape including side arms 1^a. These arms are connected at their upper ends by a heavy ring or collar 2 in which is secured by set screw 2^a a tubular member 3^a through which is threaded a pointed rod 3 provided with a handle 4. A block 5 is secured between the lower end portions of arms 1^a and receives a tubular member 6 secured in adjustment 45 through the block by set screw 7. A pointed anchor rod 8 is slidably mounted through member 6 and is secured in adjustment therein by a set screw 9. The rod 8 and member 6 provide a telescoping anchor rod whereby the machine may be accommodated 50 to rooms of unusual height.

The frame 1 provides supporting means for the feed shaft and associated parts. A disc 10 is provided with a central pin 11 which projects through a plate 12 having lateral sleeves 13 which fit about arms 1^a of frame 1 thus providing a slidable mounting for the disc on the frame. Sleeves 13, and consequently plate 12 and disc 10, are secured in adjustment on arms 1^a by means of set screws 14, or in any other suitable or preferred manner. The disc 10 is thus mounted on frame 1 for vertical adjustment and the disc is also mounted to turn about a horizontal axis on pin 11, a nut or other suitable abutment member 15 being 60 secured on pin 11 adjacent to the outer face of plate 12 to prevent withdrawal of this pin from the plate. Plate 12 is in the form of a disc, being disposed concentric with pin 11 and provided with a plurality of 65 radially projecting teeth 16. These teeth are equally spaced to receive between them finger 17^a of one arm of an angle lever 17 pivoted at its angle, at 18, on disc 10. The other arm of this lever operates between 70 disc 10 and a guard strip 19 secured to the disc. A tension spring 20 connects arm 17^b of lever 17 to guard strip 19 and acts to normally hold finger 17^a in engagement between two adjacent teeth 16 of plate 12. 75 By grasping arm 17^b of lever 17 and moving it in proper direction to disengage finger 17^a from plate 12, the disc 10 may be readily turned about pin 11 so as to adjust the feed shaft and associated parts, hereinafter referred to, at the desired angle. 80

Disc 10 is provided at the opposite face thereof to pin 11 with a block 21 from which extends a stub-shaft 22. This block provides a bearing for neck 23 of a bevel gear 24 the body 25 of which is rotatably mounted in a pillow block 26 secured to disc 10. The gear 24 is provided, within body 25 and neck 23, with inwardly projecting ribs 27 which fit into grooves 28 extending longitudinally of a threaded feed shaft 29. A bevel pinion 30 is rotatably mounted on stub-shaft 22 and an operating crank 31 is secured to this pinion for rotating the same. Shaft 29 extends through a split sleeve or 90 nut 32. This nut is formed in two sections 33 and 34 which are hingedly connected together and to disc 10 by means of a pintle 35 passing through ears 36 formed on the disc and interengaging sleeves carried by 95 100 105 110

sections 33 and 34 of the nut. A bolt 37 is secured through section 34, section 33 being provided with a slot 33^b to accommodate bolt 37. A wing nut 38 is threaded onto the bolt so that the bolt and the nut co-operate to force the two sections 33 and 34 of the split nut together thus closing the nut about shaft 29, the shaft being threaded through this nut. Disc 10 is provided with a suitably shaped opening 39 to permit the split nut to be opened, when desired, at which time the hinge mounting of this nut is preferably positioned downwardly so that by threading wing nut 38 off of bolt 37, the nut 32 will open by gravity thus releasing shaft 29 to permit the same to be readily moved through gear 24 for withdrawing the boring tool or bit. As will be noted more clearly from Figs. 5 and 6, disc 10 is provided with fingers 40 which project into opening 39, these fingers being positioned to be clamped between extensions 33^a and 34^a of sections 33 and 34, respectively, of nut 32. This provides simple and efficient means whereby the nut is effectually secured by the simple act of closing or clamping it about the shaft 29 thus insuring proper aligning of this nut with gear 24. When split nut 32 is in operative position and pinion 30 is rotated, shaft 29 is rotated and is simultaneously fed through split nut 32. A suitable boring tool or bit 41 is secured on shaft 29 so that when the machine is set up in proper position adjacent to the working face in the mine, as illustrated in Fig. 1, by turning crank 31 the bit is rotated and is simultaneously forced into the coal so as to bore out a hole therein. The plate 12 and associated parts permit ready adjustment of disc 10 to the desired height,

after which the disc can be readily adjusted about pin 11 so as to accurately position shaft 29 at the proper angle for drilling or boring the hole desired. After the hole has been bored to the proper depth, by opening split nut 32 shaft 29 is released from this nut and the shaft may be readily moved or slid through gear 24 so as to withdraw the bit 41 from the hole. If desired, the gear 24 can be motor-driven, any suitable or well known type of motor and driving connections being employed for this purpose. As will be understood, changes in details of construction and arrangement of parts of the invention may be resorted to without departing from the field and scope of the same, and I intend to include all such variations, as fall within the scope of the appended claims, in this application in which a preferred form only of my invention is disclosed.

What I claim is:—

In a machine of the character described, a supporting disc, said disc being provided with an opening, a split nut including two sections hingedly connected together and to the disc at one end, and in alignment with said opening, the opening permitting the inner section of the nut to be moved into open position, means for forcing said sections toward each other and for securing them together at the other end thereof, the sections of the nut being provided with elements disposed to engage with the disc adjacent to the opening therein so as to clamp the nut to the disc when said nut is closed, a feed shaft threaded through said nut, and means for rotating said shaft.

In testimony whereof I affix my signature.
ELLIS PLUMLEY.
